(57) **CLAIM**

The ornamental design for a multimode daylight sensor, as shown and described.

DESCRIPTION

FIG. 1 is a upper perspective view of a multimode daylight sensor showing my new design;

FIG. 2 is lower perspective view thereof;

FIG. 3 is a front view thereof;

FIG. 4 a left side view, the right side being a mirror image thereof;

FIG. 5. is a rear view thereof;

FIG. 6 is a top plan view thereof;

FIG. 7 is a bottom plan view thereof;

FIG. 8 is a upper perspective view of a second embodiment thereof;

FIG. 9 is a lower perspective view thereof;

FIG. 10 is a front view thereof;

FIG. 11 is a left side view, the right side being a mirror image thereof;

FIG. 12 is a rear view thereof;

FIG. 13 is a top plan view thereof; and,

FIG. 14 is a bottom plan view thereof.

The evenly sized broken lines on the drawings depict portions of the sensor that form no part of the claimed design.
